(57) **CLAIM**

The ornamental design for a smart watch with earphones, as shown and described.

DESCRIPTION

FIG. 1 is a perspective view of a smart watch with earphones showing the new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the earphones portion of the smart watch with earphones shown separately to show aspects of the design that are not visible when combined;

FIG. 10 is another perspective view thereof;

FIG. 11 is a front elevation view thereof;

FIG. 12 is a back elevation view thereof;

FIG. 13 is a left side elevation view thereof;

FIG. 14 is a right side elevation view thereof;

FIG. 15 is a top plan view thereof;

FIG. 16 is a bottom plan view thereof; and,

FIG. 17 is a perspective view of the smart watch with earphones in an open position.

The broken lines depict portions of the smart watch with earphones that form no part of the claimed design.
